UNITED STATES PATENT OFFICE.

ALPHONSO VUOLO, OF MALDEN, MASSACHUSETTS.

SANITARY HOLDER FOR TOILET ARTICLES AND THE LIKE.

Application filed April 28, 1925. Serial No. 26,384.

This invention relates to improvements in holders for toilet articles and the like, such as, tooth brushes, nail brushes, tubes of tooth paste, and one of the objects there-
5 of is to provide a holder which will securely hold the articles, but from which they can be readily removed and replaced.

Another object of the invention is to provide a holder for toilet articles and the like
10 in which the articles will be normally held in separated position and inclined toward the axis of the holder so that they will not tend to fall out of the holder.

A further object of the invention is to
15 provide a sanitary container for toilet articles which will protect them from germs and dust and from which they can be readily removed for use and easily replaced.

A further object of the invention is to
20 provide a holder for sanitary articles which can be readily introduced into a glass or other receptacle carried by a bracket upon the wall and from which the holder can be readily withdrawn to permit the removal of
25 the article desired.

Another object of the invention is to provide a sanitary holder of the character described having a cover provided with a flange surrounding the upper end of the
30 receptacle and having ventilating ports to permit the air to enter the receptacle laterally, while dust is prevented by the cover from settling upon the articles in the holder.

Other objects and features of the invention will more fully appear from the following description and the accompanying drawing and will be particularly pointed out in the claims.

A preferred embodiment of the invention
40 is illustrated in the accompanying drawing, in which,—

Fig. 1 is a vertical sectional view of a container, such as a glass or tumbler having therein a removable holder for toilet articles, the holder being shown partly in elevation;

Fig. 2 is a horizontal sectional view through the receptacle and holder on line 2—2 Fig. 1, viewed from the top;

Fig. 3 is a view similar to Fig. 1 of a modified form of holder; and,

Fig. 4 is a horizontal sectional view through the receptacle and holder on line 4—4 Fig. 3, viewed from the top.

The invention comprises essentially a holder for toilet articles and the like adapted to be introduced into a usual form of

tumbler, the holder being so constructed that the articles supported by it will incline from their bases toward the axis of the holder, means also being provided to prevent lateral displacement of the upper portions of the article.

In the embodiment of the invention illustrated in Figs. 1 and 2 the holder comprises a standard form of a series of plates 1 extending radially from the axis 2 of the holder and preferably secured together at their abutting sides. Any desired number of such plates can be employed, six being illustrated in the accompanying drawing. The holder is provided with a base so constructed that when the lower ends of the articles are resting upon said base they will be caused to lean toward the vertical axis thereof. As the articles are to be placed in the separate compartments between adjacent radial plates the upper ends of the articles which rest against the plates will be prevented from lateral displacement.

Preferably the base 3 is of conical form, the wall of the cone diverging downwardly and outwardly from the axis of the standard and is provided with a preferably cylindrical rim 4 which is secured to the outer edges of the vertical plates 1. The lower circular edge of the base is adapted to rest upon the bottom of a glass tumbler 5, or other suitable receptacle, and desirably apertures 6 are provided adjacent the periphery of the base to permit any water which otherwise would accumulate in the lower portion of the holder to escape into the bottom of the receptacle.

The holder desirably is provided with a cover 7 likewise of conical form and secured to the upper ends of the plates 1. The apex of the cover is provided with a handle 8, preferably in the form of a ring, by means of which the holder can be raised out of and introduced into the receptacle or supported upon a suitable hook. The holder desirably is somewhat longer than the receptacle so that the conical portion of the cover 1 is located well above the upper end of the receptacle. The cover is provided with a downwardly extending annular flange 9, preferably of cylindrical form, which has a series of ports 10 to permit the passage of air into and out of the receptacle so that the articles will readily dry although enclosed within the receptacle.

The modified construction illustrated in

Fig. 3 is of somewhat similar character except that the standard instead of being formed of a series of radial plates extending from the base of the cover to the receptacle 5 comprises a vertical rod 10 to the lower end portion of which a series of radial plates 11 are secured, the lower edges of the radial plates 11 being secured to the upper surface of the conical bottom 12 which is adapted 10 to rest at its periphery upon the base of the glass 13 or other receptacle. The base of this holder is also provided with an upwardly extending flange 14 which likewise is secured to the outer edges of the vertical plates 11.

A cover 15 desirably of conical form is secured to the upper end of the rod 10 and is provided at its apex with a handle 16 desirably in the form of a ring. The cover 20 15 has a downwardly extending flange 17 provided with a series of apertures 18 and the holder is of such length that the ports or apertures 18 are located above the top of the receptacle.

In this construction, however, different means are provided for retaining the articles in separated position and against lateral displacement. As illustrated this means comprises a spider 19 having a series of pairs 30 of resilient arms 20 and 21 diverging from the spider outwardly to about midway of their length, then converging for a distance and terminating in divergently curved ends. By reason of this construction the articles, 35 such as, tooth brushes and the like, can be placed in the holder with their lower ends resting upon the base of the holder and the upper portions of the articles readily thrust between the curved ends of the resilient members and when introduced are securely 40 retained in position.

In this construction, as in that disclosed in Figs. 1 and 2, the base of the holder is provided adjacent its periphery with a series 45 of apertures 22 to permit any liquid which might otherwise accumulate in the base portion of the holder to escape into the receptacle.

In the use of the device an ordinary tumbler, such as are commonly used in bath- 50 rooms and supported upon brackets on the walls thereof, may be employed as a receptacle and the holder with the toilet articles supported therein introduced at the top of the receptacle, the base of the holder resting upon the bottom of the receptacle.

When it is desired to use one or more of the articles in the holder the holder can be 60 readily raised by its handle a sufficient distance to permit the article to be grasped and removed from the holder. When the articles are to be restored to the holder the holder can again be raised a sufficient distance to permit the article to be readily placed in it. In such instances the lower

end of the article is placed upon the base and by reason of the downward and outward inclination of the base the lower end of the article slides outwardly until it engages the rim of the base. The upper end of the article thereby tends by gravity to lean toward the axis of the holder and in the construction illustrated in Figs. 1 and 2 the upper ends of each article rest against the converging walls of the vertical plates 1. 70 In the construction illustrated in Figs. 3 and 4 the upper portion of the article can be pressed against the resilient gripping members which will yield sufficiently to enable the article to be securely engaged by the 75 arms thereof so that when the holder is withdrawn or removed from the receptacle the toilet articles cannot fall out.

While the holder herein described is primarily intended to be used with a receptacle 80 and to form a cover therefor it will be obvious that the holder itself may be used separately or sold separately as the base of the cover or the cover alone may be so constructed as to fit a glass of standard size. 85 It will also be obvious that the holder itself may be supported by its handle or ring from a suitable bracket.

It will be understood that the embodiment 90 of the invention disclosed herein is of an illustrative character and is not restrictive, and that various changes in form, construction and arrangement of parts may be made within the spirit and scope of the following claims.

Having thus described the invention, what is claimed as new, and desired to be secured by Letters Patent, is:

1. A holder for toilet articles and the like comprising a standard provided with means to engage the upper portions of the article and prevent the lateral displacement thereof, a base secured to said standard having means to cause the articles resting upon said base to lean toward the vertical axis of said 105 holder.

2. A holder for toilet articles and the like comprising a standard having a cover provided with an upwardly extending handle member and having means to engage the upper portions of the articles and prevent lateral displacement thereof, a base secured to said standard inclined downwardly and outwardly from the vertical axis thereof and provided with a rim and acting to cause the articles resting upon said base to lean toward the vertical axis of said holder.

3. A holder for toilet articles and the like comprising a standard having radially extending vertical plates and a downwardly 125 and outwardly extending conical base provided with a rim and acting to cause the articles resting upon said base to lean toward the vertical axis of said holder.

4. A sanitary container for toilet articles 130

and the like comprising a receptacle, a holder removably mounted therein having a standard provided with means to engage the upper portions of the articles and prevent lateral displacement thereof, a base secured to said standard inclined downwardly and outwardly from the vertical axis thereof adapted to rest upon the base of said receptacle and provided with a rim and acting to cause the articles resting upon said base to lean toward the vertical axis of said holder and a cover for said receptacle secured to said standard located at such distance from said base as to provide a space between the cover and the top of the receptacle and having a downwardly extending flange surrounding the top of said receptacle so constructed as to provide means for ventilating said receptacle.

5 5. A sanitary container for toilet articles and the like comprising a receptacle, a holder removably mounted therein having a standard provided with means to engage the upper portions of the articles and prevent lateral displacement thereof, a base secured to said standard inclined downwardly and outwardly from the vertical axis thereof adapted to rest upon the base of said receptacle and provided with a rim and acting to cause the articles resting upon said

base to lean toward the vertical axis of said holder, a cover for said receptacle secured to said standard in such position that the body of the cover is above and separated from the top of the receptacle when the base of the holder rests upon the base of the receptacle and a downwardly extending flange on said cover surrounding the top of the receptacle and provided with ventilating ports above the top of the receptacle.

10 6. A sanitary container for toilet articles and the like comprising a receptacle, a holder removably mounted therein having a standard provided with means to engage the upper portions of the articles and prevent lateral displacement thereof, a base secured to said standard inclined downwardly and outwardly from the vertical axis thereof adapted to rest upon the base of said receptacle and provided with a rim and with 15 apertures adjacent the periphery of said base adapted to permit the liquid to flow from the holder into the receptacle and a cover for said receptacle secured to said standard having a downwardly extending 20 flange surrounding the top of said receptacle.

25 In testimony whereof, I have signed my name to this specification.

30 ALPHONSO VUOLO.
